United States Patent Office

Des. 220,760
Patented May 18, 1971

220,760

MODULAR HOME

John M. Evans, Fort Lauderdale, Fla., assignor to Behring Corporation, Fort Lauderdale, Fla.

Filed Apr. 10, 1970, Ser. No. 22,371

Term of patent 14 years

Int. Cl. D25—04

U.S. Cl. D13—1

FIG. 1

FIG. 2

FIG. 3

FIG. 1 is a perspective view of the modular home in accordance with one embodiment of the invention;

FIG. 2 is a perspective view of the modular home taken from a different angle than FIG. 1; and

FIG. 3 is a perspective view of the modular home taken from a still different angle.

I claim:

The ornamental design for a modular home, as shown.
